PHOTOTUBE

Bernard Salzberg, East Orange, N. J., assignor, by
mesne assignments, to Radio Corporation of
America, New York, N. Y., a corporation of
Delaware

Application November 14, 1936, Serial No. 110,805

4 Claims. (Cl. 250—27.5)

My invention relates to light sensitive electron discharge devices, more particularly to phototubes in which secondary emission amplification is produced.

5 In the conventional phototube making use of secondary emission amplification, a light sensitive electrode or photocathode which releases photoelectrons when exposed to light is oppositely disposed to a secondary emitting electrode 10 or auxiliary cathode coated with material which releases secondary electrons when struck by the photoelectrons from the photocathode. A rod or grid-like collecting electrode or anode is placed between the photocathode and the auxiliary 10 cathode. The usual arrangement of the electrodes and the usual shape of the electrodes do not promote optimum characteristics from the standpoint of obtaining maximum light on the photocathode, of preventing useless dissipation 15 of both photoelectrons and secondary electrons, of obtaining high secondary emission and collecting the maximum number of secondary electrons at low collector voltages and obtaining low inter-electrode capacitances.

20 To obtain an efficient secondary emission amplification phototube with the most desirable characteristics the electrodes should be so constructed and positioned that as much of the available light as possible reaches the photocathode 20 and so that as much of the photoelectron emission as possible strikes the secondary emitter cathode, that is so that as little of it is diverted or intercepted by the collector as possible. To obtain good characteristics it is also necessary 25 that the greatest possible ratio of secondary electrons to primary electrons at the secondary emission electrode or cathode is obtained and that as much of the secondary emission current as possible is collected with a minimum voltage at 30 the collector or anode. It is also desirable to reduce the capacitance between the electrodes.

35 The object of my invention is to provide an improved type of secondary emission amplification phototube which satisfies the above conditions 40 for an efficient phototube.

45 The novel features which I believe to be characteristic of my invention are set forth with particularity in the appended claims, but the invention itself will best be understood by reference 50 to the following description taken in connection with the accompanying drawing in which Figure 1 is a perspective with the envelope partially broken away of a phototube made in accordance with my invention, and Figure 2 is a transverse 55 section taken along the line of 2—2 in Figure 1.

5 One embodiment of a phototube made in accordance with my invention comprises an envelope 10 provided with the usual base 11 and stem 12. Supported from the stem 12 is a conventional semicylindrical or arcuate shaped photocathode 13 which may be coated on its inner or concave surface with any conventional light sensitive coating, such as caesium for example.

10 In accordance with my invention I dispose oppositely to the photocathode 13 and preferably coaxial therewith a secondary emitting electrode 14 also preferably semi-cylindrical or arcuate shaped, although it could be flat, and coated on its convex surface which is first oxidized and then coated with an alkali metal film, for example 15 caesium, this coated convex surface being oppositely disposed to the concave surface of photocathode 13. A shiny surface also provides a good 20 secondary emitting surface. Mounted parallel to either edge of the secondary emitting electrode 14 but outside of any line normal to its surface are a pair of coextensive rectangularly shaped 25 collector electrodes or anodes 15 and 16. The secondary emitter electrode 14 is maintained at a positive potential with respect to the photocathode 13 by means of the voltage 17 and the 30 collector electrodes 15 and 16 are in turn maintained positive with respect to the secondary emitting electrode 14 by means of the source of voltage 18.

35 As a result of the electrode shape and field distribution between electrodes the photoelectrons are focused into a beam from the photocathode onto the emitting surface of the secondary emitting electrode 14 and are not dispersed. Because 40 the collectors 15 and 16 are disposed outside the focus of the beam from the photocathode they do not interfere materially with the stream of photoelectrons to the secondary emitting electrode 14. The anodes are sufficiently close to the secondary 45 emitter cathode so that it is not necessary to use a very high voltage to overcome the space charge drop caused by the secondary electrons and to collect the secondary electrons from the secondary electrode. Because the secondary emitter cathode surface is convex space charge is diffused and the secondary emission current saturates sharply, that is a lower collector voltage is needed to obtain saturation or maximum collector current than in case the surface of the secondary emitter 50 electrode were reversed so that its concave surface faced the concave surface of the photocathode and was coated on its concave surface with the emitting material. The distance between the photocathode and the collector is made as small 55

as consistent with capacitance requirements. The focusing structure promotes low interelectrode capacitance since the collector and auxiliary cathode need be made only large enough to accommodate the focused electron beam and the emitted secondaries.

While I have indicated the preferred embodiments of my invention of which I am now aware and have also indicated only one specific application for which my invention may be employed, it will be apparent that my invention is by no means limited to the exact form illustrated or the use indicated, but that many variations may be made in the particular structure used and the purpose for which it is employed without departing from the scope of my invention as set forth in the appended claims.

What I claim as new is:

1. A phototube including an envelope containing a photocathode, an oppositely disposed secondary emitting electrode and a collector electrode adjacent said secondary emitting electrode but outside any line normal to the emitting surface of said secondary emitting electrode.
2. A phototube including an envelope containing an arcuate shaped photocathode having a light sensitive coating on its concave surface and an oppositely disposed secondary emitting cathode having its surface opposite the concave sur-

face of the photocathode coated with emitting material, and a collector electrode adjacent the edge of the secondary emitting electrode but outside a line normal to the emitting surface of said secondary emitting electrode.

3. A phototube including an envelope containing an arcuate shaped photocathode having its concave surface coated with light sensitive material, an oppositely disposed arcuate shaped secondary emitting electrode having a convex surface coated with electron emitting material and collector electrodes adjacent the edges of the convex surface of said secondary emitting electrode outside a line normal to said convex surface.

4. A phototube including an envelope containing a semi-cylindrical photocathode coated with light sensitive material on its concave surface, a semi-cylindrical secondary emitting electrode coaxial with said photocathode and having its convex surface oppositely disposed to the concave surface of said photocathode and coated with an electron emitting material and a pair of rectangular plates parallel to the longitudinal edges of the semi-cylindrical secondary emitting electrode and coextensive therewith outside of any line normal to the convex surface of said secondary emitting electrode.

BERNARD SALZBERG.
